UNITED STATES PATENT OFFICE.

THOMAS C. MORRIS, OF ATLANTA, GEORGIA, ASSIGNOR TO PETER VREDENBURGH, JR.,
OF VREDENBURGH, ALABAMA.

MOUNTING FOR FEEDING-ROLLERS.

1,278,979.

Specification of Letters Patent. Patented Sept. 17, 1918.

Application filed November 23, 1917. Serial No. 203,586.

To all whom it may concern:

Be it known that I, THOMAS C. MORRIS, a citizen of the United States, residing at city of Atlanta, county of Fulton, and State of Georgia, have invented a certain new and useful Improvement in Mountings for Feeding-Rollers, of which the following is a full, clear, and exact description, such as will enable others skilled in the art to which it appertains to make and use the same, reference being had to the accompanying drawings, forming part of this specification.

This invention relates to certain improvements in feed rollers for lumber machines of the type illustrated in the patent to Thomas A. Coleman, No. 1,208,294.

As is well known in the art, rollers of the type commercially known as the Coleman feed rollers are characterized by a construction which is designed to facilitate the installation of the roller, and its repair, without necessitating its removal from the machine. The Coleman construction includes a shaft which is journaled in the machine, and upon which are mounted one or more drums or carriers in which are removably seated the engaging elements or tooth bars, the same being retained in their seats by the clamping action of relatively adjustable members which coöperate with their extremities. These rollers are frequently sold to replace, in machines already installed, rollers of other types.

The purpose of my invention is to improve or add to the Coleman construction in certain particulars which will enable it to meet certain conditions obtaining in machines designed for other sorts of rollers. The Coleman construction requires that the carriers be adjustable longitudinally on the shaft so as to facilitate the removal of the engaging elements. This necessitates the intermediate portion of the shaft being larger than the end portions, in order that the drums or carriers may be slipped onto the shaft. In many machines designed for other forms of rollers, however, the bearings or boxes in which the shaft is journaled, are of considerably greater diameter than that permitted in a Coleman roller of the desired size. The present improvement is designed to provide an arrangement whereby the journal portions of the shaft may be equipped for mounting in bearings of excessive size. The present improvement contemplates further

the provision of a construction wherein, in a roller so equipped, the screw threads upon which the adjustable terminal clamping member is mounted, are protected from injury, and the roller in its entirety is held against longitudinal movement in its bearings.

Other and further objects will be obvious or pointed out hereinafter, reference being had to the accompanying drawings, in which—

Figure 1 is a detail in the nature of a partial longitudinal section through a bearing and end portion of a Coleman feed roller containing my invention; and

Fig. 2 is a cross section of the same taken substantially on line 2—2 of Fig. 1.

Referring to these illustrations in detail by the reference characters applied, it will be understood that the numeral 1 designates the shaft of the Coleman feed roller, upon which shaft is mounted the drum 2 having the customary longitudinal slots 4 for the reception of the tooth bars or engaging elements 5. Adjacent the extremity of the drum the shaft is provided with the screw thread 6 upon which the clamping collar 7 is mounted for movable coöperation with the extremities of the tooth bars 5 and the adjacent drum 2. When turned up, the clamping collar 7 engages the drum 2 and the extremities of the tooth bars in the manner characteristic of the Coleman feed roller, and said clamping collar may be backed away from the drum to clear the extremities of the tooth bars to permit their removal from the slots when so desired. The journal portion of the shaft which I designate by the numeral 1^a extends beyond the screw-threaded portion and, necessarily, is of less diameter than the screw-threaded portion and the portion which supports the drums 2. In order to accommodate this journal portion of the shaft to a box or bearing, as is frequently necessary in a machine not designed specially for the mounting of the Coleman feed roller, I apply on the journal portion 1^a a bearing sleeve 8. This sleeve is driven over the journal portion 1^a and is turned on to the screw-threaded portion 6 to the desired extent, leaving the necessary clearance between the inner extremity of the sleeve and the adjacent face of the clamping collar 7 to permit the required outward movement of the latter. This sleeve 8 is

then turned down on its outer face to the proper diameter for installation in the bearing 9. In conjunction with this arrangement, for the purpose of retaining the shaft 5 against longitudinal movement in the bearings, and to afford the necessary protection for the screw threads 6, I provide a bearing collar 10 which is rotatably mounted upon the bearing sleeve 8. This bearing collar has 10 a bearing face 10^a extending normal to the shaft and adapted to contact with the adjacent face of the bearing or box. The bearing collar 10 is counter-bored from its other face to accommodate a shoulder 8^a formed adjacent 15 the inner extremity of the bearing sleeve 8, the arrangement operating to hold the bearing collar 10 against movement inwardly on the shaft toward the clamping collar 7. Seated in the bearing collar 10 are one or more dowels 11 which extend inwardly and have adjustable co-operation with the clamping collar 7 by means of the channels 12 arranged in the latter for the reception 20 of the dowels. The clamping collar 7 is provided with the customary spanner seats 7^a whereby it may be engaged to be turned on the screw thread 6. When it is desired to back off the clamping collar to release the engaging elements, the bearing 25 collar 10 will be rotated with the clamping collar by virtue of the engagement of the dowels in the channels 12, while the extent of said channels will permit the movement of the clamping collar toward the bearing 30 collar. Flush with its outer face the clamping collar is provided with the annular flange 14 which extends about the perimeter of the bearing collar 10, forming a close sliding fit therewith, and affording a complete cover 35 and protection for the portion of the screw 40 thread 6 intermediate the collars.

As a means for preventing longitudinal movement of the shaft away from the bearing, I extend the journal portion 1^a beyond the outer extremity of the bearing or box, and there affix to the shaft the set collar 15, same being held by a counter-sunk set screw 16. The set collar 15 has its inner face normal 45 to the shaft and adapted to bear against the outer extremity of the bearing 9, by virtue of which engagement the shaft is retained against longitudinal movement inwardly from the bearing.

It will be understood that by virtue of this 50 arrangement of parts the roller may be accommodated to a wide variety of boxes or bearings, as, irrespective of the over-all diameter of the operating portion of the roller, the diameter of the journal portion 55 may be varied as required. Furthermore, by variations in the width of the bearing collar 10, and by virtue of the adjustability 60 of the set collar 15, the roller may be ac-

commodated to bearings or boxes of any width. The arrangement of bearing collar, 65 clamping collar, and bearing sleeve, also affords complete protection to the thread upon which the clamping collar must operate, preventing its injury in any such fashion as may interfere with the facilities for permitting the removal and replacement of the tooth bars. 70

Inasmuch as the dowels hold the clamping collar and the bearing collar for rotation together on the shaft, the operative engagement of the bearing collar with the face of the bearing will act to keep the clamping collar screwed up tight, it being understood that the thread on the shaft is pitched toward the bearing. 75

Other advantages of this construction will be readily apparent to those skilled in the art, as will various modifications and adaptations of the particular arrangement shown. It is my purpose and intention in the following claims to comprehend all of such various modifications and adaptations as are properly within the true scope and spirit 85 of my invention. 90

What I claim is:

1. In a feeding roller including the shaft, the drum carried thereby, and the clamping collar having screw-thread engagement with the shaft in association with the drum, the combination of a bearing sleeve mounted on the shaft in association with the clamping collar, and formed to provide a journal for the shaft, and means associated with said bearing sleeve for engaging a bearing in which the shaft is journaled to prevent longitudinal movement of the latter. 95

2. In a feeding roller including the shaft, the drum carried thereby, and the clamping collar having screw-thread engagement with the shaft in association with the drum, the combination of a bearing sleeve mounted on the shaft and shaped to form a journal for the shaft, and means associated with said sleeve to prevent contact of the screw-threaded portion of the shaft with a bearing in which the shaft is journaled. 105

3. In a feeding roller, the combination with the shaft, the drum carried thereby, and the clamping collar having screw-thread engagement with the shaft in association with the drum, of a bearing sleeve mounted on the shaft in association with the screw-threaded portion thereof and shaped to provide a journal for the shaft, and a collar mounted on the bearing sleeve in association with the clamping collar and arranged for co-operation with a bearing in which the shaft is journaled. 115

In testimony whereof I hereunto affix my signature this fifth day of November, 1917. 125

T. C. MORRIS.
